APPARATUS FOR REMOVING AIR FROM VISCOSE SOLUTION

Lawrence Louis Malm, Rocky River, Ohio, assignor to Industrial Rayon Corporation, Cleveland, Ohio, a corporation of Delaware

Application May 17, 1952, Serial No. 288,392

3 Claims. (Cl. 183—2.5)

1

This invention relates to an apparatus for the removal of air and other gases dissolved and entrained in liquids. More particularly, it relates to the continuous removal of air and other gases from viscous liquid solutions such as viscose.

In the process of preparing viscose solutions for the spinning of synthetic fibers, gas and air become entrained in such solutions in the form of bubbles. Should these gas and air bubbles be permitted to remain, broken filaments in the spun yarn would result when the viscose solution is extruded through the holes of spinnerets. Yarn thus produced has a varying number of filaments and is therefore not of uniform quality.

Various methods have been proposed to remove these gases from viscose spinning solutions. One of the methods comprises subjecting a batch of viscose in a receptacle to a vacuum. In another method the viscose solution is agitated while subjected to a vacuum. Still various other methods employ baffles, plates, cones, etc. as means for spreading the viscose solution into a thin film with or without a supporting and flow directing surface, then subjecting such thin film of viscose to a vacuum. These aforementioned deaerating methods are generally not satisfactory since through their practice utilized apparatuses are generally frequently taken out of service for cleaning and the gases are not substantially completely removed.

In some deaerating apparatuses it is necessary to stop their operation and clean their interiors at regular intervals of adhering and hardened viscose. This is necessary because viscose on entering a tank is caused to boil because of reduced pressure created by vacuum on the tank. The boiling action frees the entrained gases and causes spattered viscose to be carried away from the surface of the liquid and deposited on the bare walls of the deaerating chamber. This forms a skin due to the aging characteristics of the viscose liquid. This skin then builds up and impedes the flow of viscose. In the event that the deaerating apparatus is not cleaned at the proper time the hardened skin breaks away from the metal surface and falls into the viscose, subsequently tending to block pumps, controls, filters, etc.

This invention has for its purpose the provision of an apparatus which is adapted to continuously and substantially more completely degasify and deaerate a flowing viscose solution and to prevent spattered viscose from becoming fixed to the interior tank walls. The deaeration is effected by causing an initial boiling of a viscose solution

2

in a limited collecting enclosure such as a channel and a trough into which the solution is initially emptied. The viscose solution is continuously fed to the channel and trough which it overflows to spread as a thin film over supporting surfaces such as the interior wall of a tank and the exterior wall of a bell shaped cylinder centrally located within the lower portion of the tank.

To prevent clinging spattered viscose a jacket is placed about the upper portion of the viscose deaerating tank. A cooling fluid is pumped through an inlet, into the jacket, circulated through the jacket, and then it is forced out through an outlet. The tank walls are wetted by the condensation of rising vapors. A sufficient quantity of cooling medium at a desired temperature to produce condensation of water vapors on the walls of the deaerating chamber is circulated through the jacket, the condensed vapors return by gravity as a water film to the main body of the flowing liquid viscose, and whatever spattered viscose hits this flowing film of condensed water it is diluted on contact and also returned to the main liquid viscose body. Spattered viscose does not remain on the tank wall but flows downwardly to rejoin the main viscose body. An additional advantage is that no additional dilution is, generally, required to compensate for the water boiled off during the deaeration since the water vapor is returned as condensate to the viscose solution. Also, condensation of the water vapors and the return of the condensate lowers the requirement in vacuum pump capacity resulting in lower cost operation.

In removal of entrained gas and air bubbles from the viscose solution a boiling and subsequent thinning of the viscose solution frees entrained gases which are being continuously evacuated. The more deeply entrained gas bubbles are yielded as the solution overflows a channel and trough as a film which is spread in a flowing thin layer on the inner surface of the tank and over the outer surface of the bell. The filming of the viscose solution allows the more minute bubbles to escape since their entrainment is in a thin layer and they are closer to the surface of the viscose so as to be more easily drawn out by the vacuum within the tank. There is provided, further, a second channel below the first mentioned channel to effect a repeated filming of the solution a second time to remove gases not already given up. Attached to this second channel there may be provided a baffle plate to

collect viscose that may become spattered during the initial boiling. The baffle redirects such spattered viscose to the flowing stream along and against the inner wall of the tank.

The invention will be better understood by reference to the following description and accompanying drawing wherein the deaerating apparatus is shown in section.

As shown in the drawing the deaerating apparatus comprises an enclosed tank 10 having a cylindrical intermediate portion 11 enclosed by a tank top 12 and tank base 13.

In the tank top 12 there is positioned a viscose inlet conduit 16 which extends substantially into the tank interior. Positioned within the tank 10 and at its upper portion is a viscose distribution manifold 17 which is attached to the viscose inlet conduit 16. Projecting from the distribution manifold 17 are a plurality of laterally extending viscose distribution tubes 18, and a downwardly extending tube 19. The distribution tubes 18 have outlets in channel 30, and tube 19 extends into trough 45.

In order to facilitate the removal of the air bubbles and gases from the viscose a vacuum means (not shown) is attached to the vacuum pipe 21 also positioned in the tank top 12. In the continuous deaeration of viscose by vacuum, the pressure in the deaerating vessel is reduced and it is controlled at a point depending upon the vacuum applied which permits a boiling of the viscose through a predetermined temperature range. This boiling action removes readily releasable gases from the viscose, as well as some water vapor.

Positioned about the top portion of the tank 10 is a jacket 24 having a cooling medium inlet pipe 25 and an outlet pipe 26. In the space 27 there is circulated a cooling medium. The cooling medium cools the upper portion of the tank 10, the cooled inner walls chill the vapor in the withdrawn gases to form a condensate on the inner wall of the tank wetting the wall, preventing the accumulation of spattered viscose and lubricating the wall surface.

Positioned in the upper portion on the interior of the tank 10 is the channel 30. Channel 30 is formed by the inner wall of tank cylinder 11 and a frustum of a cone 31 with its diverging portion 32 in contact with the inner tank wall of the tank cylindrical portion 11. Positioned below the first channel 30 is a second channel 35 formed in a like manner. The second channel 35 also has the diverging portion 37 of the frustum of a cone 36 contacting the inner wall of the tank cylinder 11. Attached to the second channel 35 is a baffle 39, also shaped as a frustum of a cone. The baffle 39 is spaced from the second channel 35 being supported by hangers 41 and it is positioned with its diverging portion 40 placed into close proximity to the diverging portion 37 of the second channel 35 and of the inner wall of tank cylinder 11.

Resting in the base 13 of the tank 10 is a bell 44 formed in such a manner so as to facilitate the spreading of viscose by means of a curved surface. At the top portion of the bell 44 there is positioned a circular trough 45. In the base of the bell 44 and in the vertical sides 47, are a plurality of openings 46. These openings allow the viscose to flow through the screen 50 to the viscose outlet 51 in the base 13 of tank 10.

In the continuous operation of the deaerating apparatus comprising this invention viscose is fed to the tank through the viscose inlet con-

duit 16 and flows to the viscose distribution manifold 17. From the manifold 17 the viscose passes through distribution tubes 18 to the channel 30 at the upper portion of the tank. The viscose overflows the converging edges of the frustum of a cone 31 of the channel 30 and flows downwardly in the form of a film and continues downwardly along the inner wall of tank cylinder 11. In its flow from the upper annular trough 30 the viscose solution tends to divide and to collect into separate but considerably thicker streams rather than as a uniformly thin cylindrical flowing stream. Baffle 39 serves to again spread and unify the various streams into a thin film. The viscose solution that flows into the trough formed by the baffle and the wall of the tank 10 flows out through the base opening as a single thin cylindrical stream of tank 10. The flow of viscose continues downwardly until it reaches the second channel 35 where, again, the viscose is caused to overflow the converging edges of the frustum of a cone 36 in the form of a thin film of liquid. The deaerated viscose solution then flows downwardly along the inner wall of the tank cylinder 11 to the tank base 13, and through the screen 50, and out through the viscose outlet 51.

Simultaneously with the feeding of viscose into the upper channel 30 viscose is also continuously fed from the manifold 17 through the distribution tube 19 into the trough 45 on the viscose spreading bell 44. The viscose overflows the trough 45 and flows in a spreading manner downwardly along the walls 47 of the bell 44 in the form of a thin film releasing gas and air bubbles. The film of viscose flowing along the wall of the bell proceeds downwardly until it reaches the base of the bell 44 and then flows through the holes 46 at the base of bell walls 47 and then through the screen 50 into the viscose outlet 51.

The interior of the tank 10 is made accessible through the side manhole cover 54. Further, the deaeration process can be checked by means of sight glasses 55, 56 positioned in the side of the tank at below the first channel 30 and at about below the top of the bell 44.

I claim:

1. A continuous viscose deaerating apparatus comprising; a tank, a jacket about the upper portion of said tank, a cooling medium circulating through said jacket, said cooling medium cooling the upper portion of said tank forming a condensate to wet the inner wall, means for placing a vacuum on said tank, a viscose inlet conduit extending into said tank, a viscose outlet in the base of said tank, a plurality of distribution tubes associated with said viscose inlet conduit, a channel in said tank at substantially its upper portion, said channel being formed by the inner tank wall and a frustum of a cone, a viscose spreading device having a generally cylindrical body portion with an enclosed top being centrally located within the lower portion of said tank, said device having on its top portion a circular trough, and said plurality of distribution tubes extending into said channel and into said circular trough for continuously supplying viscose thereto, said viscose simultaneously overflowing said channel and said trough forming a film and flowing downwardly along the inner surface of said tank and along the outer surface of said device to the outlet at the base of said tank.

2. A continuous viscose deaerating apparatus comprising; a tank, a jacket about the upper portion of said tank, a cooling medium circulating

through said jacket, said cooling medium cooling the upper portion of said tank forming a condensate to wet the inner wall, means for placing a vacuum on said tank, a viscose inlet conduit extending into said tank, a viscose outlet in the base of said tank, a plurality of distribution tubes associated with said viscose inlet conduit, a channel in said tank at substantially its upper portion, said channel being formed by the inner tank wall and a frustum of a cone, a second like channel positioned below said first channel, a viscose spreading device having generally cylindrical body portion with an enclosed top being centrally located within the lower portion of said tank, said device having on its top portion a circular trough, said distribution tubes extending into said first channel and into said circular trough for continuously supplying viscose, said viscose overflowing along the outer surface of said first channel forming a film and flowing downwardly along the inner surface of said tank then into said second channel and filmed a second time in a like manner, said viscose flowing to said outlet at the base of said tank, simultaneously said viscose overflowing said circular trough of said device is formed into a film which flows downwardly along the outer surface of said device to said outlet at the base of said tank.

3. A continuous viscose deaerating apparatus comprising; a tank, a jacket about the upper portion of said tank, a cooling medium circulating through said jacket, said cooling medium cooling the upper portion of said tank forming a condensate to wet the inner wall, means for placing a vacuum on said tank, a viscose inlet conduit extending into said tank, a viscose outlet in the base of said tank, a plurality of distribution tubes associated with said viscose inlet conduit,

a channel in said tank at substantially its upper portion, said channel being formed by the inner tank wall and a frustum of a cone, a second like channel positioned below said first channel, a baffle formed as a frustum of a cone attached to said outer surface of said second channel, a viscose spreading bell centrally located within the lower portion of said tank, said bell having on its top portion a circular trough, said distribution tubes extending into said first channel and into said circular trough for continuously supplying viscose, said viscose overflowing along the outer surface of said first channel forming a film and flowing downwardly along the inner surface of said tank then into said second channel and filmed a second time in a like manner, said viscose flowing to said outlet at the base of said tank, simultaneously said viscose overflowing said circular trough of said bell is formed into a film which flows downwardly along the outer surface of said bell to said outlet at the base of said tank, said baffle collecting spattered viscose overflowing said channels and redirecting said viscose to said tank inner wall and said outlet at the base of said tank.
